UNITED STATES PATENT OFFICE.

ROBERT HEAD, OF NEW YORK, N. Y., ASSIGNOR TO THE AEOLIAN COMPANY, A CORPORATION OF CONNECTICUT.

SOUND-RECORD AND PROCESS FOR MAKING SAME.

1,321,912.

Specification of Letters Patent.

Patented Nov. 18, 1919.

Application filed June 17, 1915. Serial No. 34,689.

To all whom it may concern:

Be it known that I, ROBERT HEAD, a citizen of the United States, residing at New York, in the county and State of New York, have 5 invented certain new and useful Improvements in Sound-Records and Processes for Making Same, of which the following is a specification.

The present invention relates to improvements in the art of making phonograph records, the features and advantages of which will hereinafter appear.

In the accompanying drawing:

Figure 1 is a diagrammatic view representing the steps of the method comprising one embodiment of the invention; and

Fig. 2 is a similar view representing the steps comprising another embodiment of the invention.

20 The invention comprises tracing, cutting or otherwise forming a sound-groove or record in a material like clay which sets or which hardens on drying or baking. Thus I take material like the finest modeling clay 25 so that the particles shall be as fine as possible to minimize any grain or roughness in the record. This material kneaded to the right consistency with water or other suitable liquid is formed into a circular tablet 30 similar to the usual wax or wax-like sound-recording tablet. The sound-groove is traced, cut or engraved in the surface of this soft clay tablet in analogous fashion and by similar means to the methods now employed 35 to form wax sound-records. Care is taken, however, that the clay-tablet is relatively dried out so that the record groove can be the more readily cut or otherwise formed in it; also so that when formed the sides or bottom of the groove will not sag or get out of shape.

Instead of clay, plaster of Paris or a cement may be used for the tablet of a consistency and condition just about to set, the 45 sound groove being formed in its surface just prior to the setting or hardening of the material. Similarly other analogously working materials may be employed.

I then take the clay sound-record and dry 50 it further or even bake it or fire it like pottery to harden and render it more permanent.

I then may make a metal casting of its 55 face which I may then use to press the commercial records like the so-called matrix is

used in the ordinary sound-record making process as represented in Fig. 1. The metal employed may be steel, cast-iron, preferably of the white variety so that the texture of the matrix may be as smooth and grainless 60 as possible, or some alloy of these to improve the flow of the metal and the quality of the casting, or some softer metal may be used having the advantage of casting at a lower temperature. In any event, the resulting 65 matrix may or may not as desired, be electrolytically faced with a film of nickel for its protection from the hot record-material when pressing the records.

Of course, my idea includes the use of any 70 molding operation and materials such as will give as perfect as possible a reproduction in the matrix of the sound-grooves in the original record of clay or equivalent materials. For example pressure may be employed during the molding operation to force the metal 75 into all the lines of the record.

Instead of molding the matrix from the original record of clay or equivalent materials, I may use it, after it has become set or 80 suitably hardened or baked, in a pantograph and thereby cut from it, used as a guide, the same record in another tablet, which may consist of a wax or wax-like material from which the commercial records can be made 85 as usually by electrotyping and pressing; or said pantographed record may consist of a metal such as soft steel—which may then be hardened. A thin nickel or steel plate or roller may then be pressed or rolled into the 90 hardened grooves to form the reverse, that is a matrix, which then, after being hardened if desired, may be backed up or otherwise treated to convert it into a practical matrix for pressing the finished records, the 95 method as thus carried out being represented in Fig. 2.

The foregoing is applicable to the production both of the so-called hill and dale and the lateral or zig-zag records. By clay-like 100 in the claims I include clay, plaster of Paris and the like. Of course changes and modifications might be made in the above that are nevertheless within the spirit of this inventive disclosure and these I mean to cover under the doctrine of equivalents by the following claims. Further, certain steps might be used without the others, or in different order or arrangement, or in connection with other or equivalent steps or means.

What I claim is:

1. The process which comprises originally cutting a sound groove in a blank of clay-like material while such material is relatively soft, and then setting said material to harden it.
2. The process which comprises originally recording a sound groove in a clay-like material while such material is plastic, and then drying said material.
3. The process of recording sound which comprises originally recording the sound in the form of a groove in a clay-like material

while such material is relatively soft, and then baking said material. 15

4. The process which comprises recording a sound groove in a clay-like material while such material is relatively soft, then setting said material to harden it, and finally casting therefrom a matrix for the production of 20 commercial records.

In testimony whereof, I have signed my name to this specification this 16th day of June, 1915.

ROBERT HEAD.
